(57) **CLAIM**

The ornamental design for a fence attachment assembly for canine containment, as shown and described.

DESCRIPTION

FIG. 1 is a front, left perspective view of a right bracket of a fence attachment assembly for canine containment depicting my new design;

FIG. 2 is a front view of the right bracket depicted in FIG.

1 of the fence attachment assembly for canine containment;

FIG. 3 is a rear view of the right bracket depicted in FIG. 1

of the fence attachment assembly for canine containment;

FIG. 4 is a left side view of the right bracket depicted in FIG.

1 of the fence attachment assembly for canine containment;

FIG. 5 is a right side view of the right bracket depicted in

FIG. 1 of the fence attachment assembly for canine containment;

FIG. 6 is a top view of the right bracket depicted in FIG. 1

of the fence attachment assembly for canine containment;

FIG. 7 is a bottom view of the right bracket depicted in FIG.

1 of the fence attachment assembly for canine containment;

FIG. 8 is a front, right perspective view of a left bracket of

the fence attachment assembly for canine containment;

FIG. 9 is a front view of the left bracket depicted in FIG. 8

of the fence attachment assembly for canine containment;

FIG. 10 is a rear view of the left bracket depicted in FIG. 8

of the fence attachment assembly for canine containment;

FIG. 11 is a right side view of the left bracket depicted in

FIG. 8 of the fence attachment assembly for canine containment;

FIG. 12 is a left side view of the left bracket depicted in FIG.

8 of the fence attachment assembly for canine containment;

FIG. 13 is a top view of the left bracket depicted in FIG. 8

of the fence attachment assembly for canine containment;

FIG. 14 is a bottom view of the left bracket depicted in FIG.

8 of the fence attachment assembly for canine containment;

FIG. 15 is a front, left perspective view of the fence

attachment assembly for canine containment depicting roll-

ers, the right bracket depicted in FIGS. 1-7, and the left bracket depicted in FIGS. 8-14; FIG. 16 is a right side view of the fence attachment assembly for canine containment depicted in FIG. 15; FIG. 17 is a left side view of the fence attachment assembly for canine containment depicted in FIG. 15; FIG. 18 is a top view of the fence attachment assembly for canine containment depicted in FIG. 15; FIG. 19 is a bottom view of the fence attachment assembly for canine containment depicted in FIG. 15; and, FIG. 20 is a front, right perspective view of the fence attachment assembly for canine containment depicted in FIG. 15 installed on a fence for use. The broken line showing of a fence and a lawn in FIG. 20 depicts the environment of the fence attachment assembly for canine containment and forms no part of the claimed design. The broken line showing of fasteners in FIGS. 1, 2, 4-9, and 11-20 depicts portions of the fence attachment assembly for canine containment forming no part of the claimed design. The dot-dash-dot lines in FIGS. 15, and 18-20 represent a symbolic break. The portion between the break lines forms no part of the claimed design.
